UNITED STATES PATENT OFFICE.

HARRY A. HAMILTON, OF ROCHESTER, NEW YORK, ASSIGNOR TO HICKOK MANUFACTURING COMPANY, INC., OF ROCHESTER, NEW YORK, A CORPORATION OF NEW YORK.

DISPLAY RECEPACLE FOR A BELT SLIDE WITH AN ATTACHED CHAIN.

Application filed December 11, 1923. Serial No. 680,054.

To all whom it may concern:

Be it known that I, HARRY A. HAMILTON, a citizen of the United States, and resident of Rochester, in the county of Monroe and State of New York, have invented certain new and useful Improvements in Display Receptacles for a Belt Slide with an Attached Chain, of which the following is a specification.

10 The present invention relates to a display receptacle for a belt slide with an attached chain, and an object of the invention is to provide a receptacle in which the belt slide and chain will be displayed to the best advantage, while, at the same time, permitting them to be shipped in a display receptacle without displacement from their displayed positions.

To these and other ends, the invention consists of certain parts and combinations of parts, all of which will be hereinafter described: the novel features being pointed out in the appended claims.

In the drawings:

25 Fig. 1 is a plan view of the body of the receptacle with a fragment of the cover shown;

Fig. 2 is a plan view of the body of the receptacle with the belt slide and chain in position thereon;

30 Fig. 3 is a sectional view through the receptacle with the cover closed; and

Fig. 4 is a detail view showing the manner in which the fastening wire is secured to the base member.

Referring more particularly to the drawings, 1 indicates a box-like body having a base member 2 therein, and a cover 3 adapted to fit over the body. Rising from the 40 base member is a projection 4 which is of rectangular construction, excepting that one corner is cut away or recessed at 5. In this

recessed portion the belt slide 6 is adapted to fit so that the chain 7 which projects from the under side of the slide may be wrapped about the portion 4 and the portion of the chain adjacent the central portion of the slide will lie against the projection, the free end of the chain being secured as is also the slide. The securing means, in this instance, 45 embodies a piece of covered wire 8 which is passed through two openings 9 in the base 2, in order that an intermediate portion of the wire may lie on the under side of the base, while the two ends project above the 50 base, one end serving as means to secure the free end of the chain while the other end is passed through the slide and secures the latter.

It is apparent that with this arrangement 60 the chain is held in a taut condition about the projection and with the belt slide is effectively displayed.

What I claim as my invention and desire to secure by Letters Patent is:

1. A display receptacle for a belt slide with chain attached, comprising a horizontal base member, a projection rigid with and rising from the base member, means for securing to the base member the free end of a 70 chain passed about the projection, and means for securing the slide to the base member to one side of the projection.

2. A display receptacle for a belt slide with a chain attached, comprising a horizontal base member, a projection rigid with and rising from the base member and having a recess extending from the top to the bottom thereof in a vertical side in which the slide may be positioned to rest against 80 the base member so that a chain may lie close to the projection at a point where it is connected to the slide.

HARRY A. HAMILTON.
